UNITED STATES PATENT OFFICE.

MARK L. TALBERT, OF MACON, GEORGIA.

VALVE-GEAR.

1,168,976.

Specification of Letters Patent. Patented Jan. 18, 1916.

Application filed April 20, 1915. Serial No. 22,721.

To all whom it may concern:

Be it known that I, MARK L. TALBERT, a citizen of the United States, residing at Macon, in the county of Bibb and State of Georgia, have invented certain new and useful Improvements in Valve-Gears, of which the following is a specification.

My invention relates to improvements in valve gears, adapted for use upon railway locomotives, while not necessarily restricted to such use.

An important object of the invention is to provide a valve gear of the above mentioned character, so constructed that when the pitman and main crank are on dead center, the steam chest valve cannot be shifted by swinging the reversing lever in either direction.

A further object of the invention is to provide a valve gear of the above mentioned character, which is simple in construction, inexpensive to manufacture, strong and durable.

Other objects and advantages of the invention will be apparent during the course of the following description.

In the accompanying drawings forming a part of this specification and in which like numerals are employed to designate like parts throughout the same, Figure 1 is a side elevation of a valve gear embodying my invention, with the pitman and main crank on dead center, Fig. 2 is a similar view with the pitman and main crank off of dead center, Fig. 3 is a perspective view of a rock-shaft and associated elements, Fig. 4 is a similar view of another rock-shaft and associated elements, and, Fig. 5 is an enlarged detail section taken on line 5—5 of Fig. 1.

In the drawings, wherein for the purpose of illustration is shown a preferred embodiment of my invention, the numeral 5 designates a cylinder arranged upon each side of the locomotive (not shown) near its front end, as is customary. Disposed upon this cylinder is a steam chest 6, containing the usual slide valve (not shown) connected with and operated by a rod 7. Mounted to reciprocate within the cylinder 5 is a piston (not shown) connected with a piston rod 8, having connection with a cross head 9, operating between guides 10, as shown. Pivotedly connected with the cross head 9 is a pitman 11 pivotedly connected with the outer end of a main crank 12, rigidly secured to a

driving wheel 13 of the locomotive. Arranged exteriorly of the pitman 11 and rigidly connected with the main crank 12 by a wrist pin 14, is an auxiliary crank 15, 60 having an auxiliary pitman 16 pivotally connected with its outer end.

Disposed near and above the guides 10 and rigidly attached to the frame-work of the locomotive is a bracket 17, shown more clearly in Fig. 3, to which is rigidly secured a curved depending support-arm or member 18. Pivotedly connected with the lower end of the support-arm 18, by a bolt 18' or the like, is the lower forked end 19' of a vertically swinging support link 19, shown more clearly in Fig. 5. This support link 19 has its upper portion slightly outwardly off-set and is provided therein with a recess 20', receiving the upper end of a suspension link 20, pivotally connected with the support link 19 by a bolt 21'. The lower end of the suspension link 20 is forked and pivotally connected with the pitman 16, at a point near and spaced from its forward end, as shown at 21.

The bracket 17 is provided with a pair of rearwardly extending knuckles 22, between which is pivoted a horizontal transverse rock-shaft 23. An approximately horizontal rocker-arm 24 is rigidly secured to the rock-shaft 23 near its outer end, and an approximately vertical rocker-arm 25 is rigidly secured to the rock-shaft 23 near its inner end, and depends therefrom, as shown. The rod 7 is pivotally connected with the lower end of the vertical rocker-arm 25. It is thus apparent that the rocker-arms 24 and 25 form in effect a bell-crank lever, for moving the rod 7. Pivotedly connected with the forward end of the pitman 16, as shown at 26, is an upwardly extending power transmitting link 27, the upper end of which is pivotally connected with the outer end of the rocker-arm 24, as shown.

Rigidly connected with the bracket 17 is a second bracket 26', carrying forwardly extending knuckles 27', through which is journaled a horizontal transverse rock-shaft 28, extending beneath the boiler of the locomotive for connection with the valve gears upon opposite sides thereof. Rigidly connected with this rock-shaft 28 are upstanding rocker-arms 29 and 29', as shown. Pivotedly connected with the rocker-arm 29', as shown at 30, is a shifting link or pitman 31, the rear end of which is forked

and pivotally connected with the support link 19, as shown at 32. Pivotally connected with the rocker-arm 29, as shown at 30', is a reach rod 33, the rear end of which is 5 pivotally connected with a reversing lever 34, suitably pivoted within the cab, as shown at 35. This reversing lever is provided with the usual latch means 36, for engagement with a toothed segment 37, as 10 shown. A valve gear is arranged upon each side of the locomotive, and as they are identical, a description of one will suffice for both, it being sufficient to state that the rock-shaft 28 which is turned by the lever 34, is 15 connected with elements of both valve gears, for operating the same.

The operation of the apparatus is as follows: When the reversing lever 34 is in the neutral or vertical position the support link 20 19 is also substantially vertical. The rotation of the auxiliary crank 15 effects a reciprocatory movement of the auxiliary pitman 16, in turn swinging the suspension link 20. The forward end of the auxiliary pitman 16, swinging upon the pivot 21, causes the link 27 to rise and fall, which through 25 the medium of the bell crank lever embodying the rocker-arms 24 and 25 shifts the slide valve in the steam chest 6, but not 30 sufficiently for introducing steam into the opposite ends of the cylinder 5. When the reversing lever 34 is swung forwardly with the main crank 12 off of dead center the support link 19 has its forward end swung 35 forwardly, whereby the suspension link 20 elevates the forward end of the auxiliary pitman 16, moving the link 27 upwardly, and swinging the bell crank lever embodying rocker-arms 24 and 25 in a direction to 40 move slide valve rod 7 rearwardly. When the reversing lever 34 is moved rearwardly from the neutral position just the reverse of this operation takes place and the slide valve rod 7 is shifted forwardly.

45 When the main crank 12 and pitman 11 are on dead center the auxiliary pitman 16 moves the suspension link 20 so that its lower pivot coincides with the lower pivot 18' of the support link 19, the suspension link and support link thus coinciding throughout the entire length. It will now

be impossible to move the slide valve rod 7 by swinging the reversing lever 34 in either direction. This is an important feature of the invention as it provides means whereby 55 fluid pressure cannot be introduced into either end of the cylinder, by operating the reversing lever, when the main crank and pitman are on dead center.

It is to be understood that the form of 60 my invention herewith shown and described is to be taken as a preferred example of the same, and that various changes in the shape, size, and arrangement of parts may be resorted to without departing from the spirit 65 of the invention or the scope of the subjoined claim.

Having thus described the invention, I claim:

In a valve gear of the character described, 70 a bracket to be secured to a locomotive and having spaced ears, a rock-shaft arranged between the ears and pivotally connected therewith and carrying approximately horizontal and vertical arms, a support-arm 75 secured to the bracket between its spaced ears and arranged between said arms and extending downwardly therebelow, a support link pivotally connected with the lower end of the support-arm, a suspension link 80 pivotally connected with the upper portion of the support link, a pitman pivotally connected with the lower end of the suspension link and extending forwardly therebeyond for a substantial distance, a connecting link 85 between the forward end of the pitman and the approximately horizontal arm of the rock-shaft, a valve rod connected with the approximately vertical arm of the rock-shaft, a vertically swinging operating member 90 having connection with the upper end of the support link to swing it in opposite directions, manually operated means to shift the operating member, and means to drive the pitman.

95 In testimony whereof I affix my signature in presence of two witnesses.

MARK L. TALBERT.
